UNITED STATES PATENT OFFICE.

EDWARD J. DE GUNTHER, OF MILWAUKEE, WISCONSIN.

VENTILATING SYSTEM FOR SANITARY TOILETS.

1,289,124.

Specification of Letters Patent. Patented Dec. 31, 1918.

Application filed December 27, 1917. Serial No. 209,079.

To all whom it may concern:

Be it known that I, EDWARD J. DE GUNTHER, a citizen of the United States, residing at Milwaukee, in the county of Milwaukee and State of Wisconsin, have invented certain new and useful Improvements in Ventilating Systems for Sanitary Toilets, of which the following is a specification.

This invention relates to certain new and useful improvements in ventilating systems for sanitary toilets.

The primary object of the invention is the provision of an automatically operated ventilating system for toilets whereby the same is ventilated from outside of the building when the toilet is not in use and from the interior of the building when in use.

A further object of the device is the provision of a ventilating system for providing a complete current of air through a toilet from one source when not in use and from another source when in use, thereby rendering the complete device sanitary at all times.

A still further object of the invention is the provision of a dual ventilating system for house toilets automatically operable by the usual drop or lid for changing the direction of ventilating air therethrough, whereby by circulation is uninterrupted, the exhausting of the ventilating medium being at a suitable elevation above the building within which the toilet is arranged, it being understood that the circulating air may be impregnated with a suitable disinfectant if desired.

With these general objects in view and others that will appear as the nature of the invention is better understood, the same consists in the novel combination, construction and arrangement of parts hereinafter more fully described, illustrated in the accompanying drawings and then claimed.

In the drawings forming a part of this application, and in which like reference characters refer to corresponding parts throughout the several views,

Figure 1 is an elevational view of the device partially broken away illustrating the same installed in a building.

Fig. 2 is an elevational view of the connecting lever and

Fig. 3 is a transverse sectional view taken upon line III—III of Fig. 2.

Referring more in detail to the drawing it will be first understood that my invention

contemplates the positioning of a tank 10 arranged beneath the floor 11 of a building 12 adapted for holding a quantity of disinfecting material such as the fluid 13 while a usual form of toilet bowl 14 is positioned within the building 12 upon the upper end of an upright pipe or stack 15 mounted upon the said tank.

An intake pipe 16 is arranged entering the tank 10 at the opposite end thereof from the stack 15 with the free end of said pipe 16 projecting above the surface of the ground 17 provided with a spaced cap 18 adapted for normally preventing foreign material from entering the pipe 16 but permitting the free passage of outside air into the tank 10 through the said intake pipe.

The usual vent pipe 19 is arranged for the bowl 14 extending to an elevated point above the building 12. A damper 20 is hinged within the tank 11 at the lower end of the pipe 12 for closing the same and is operatively connected by means of a pivot rod 21 with a lever 22 journaled upon a shaft 23 arranged within the tank 10. The drop or lid 24 of the bowl 14 is arranged thereon in the usual manner and is connected with the lever 22 by means of a curved rod 25. It will be readily understood by referring to Fig. 1 of the drawing that when the lid 24 is in its normal closed position, the rod 25 will be lowered and a damper 20 will be in its normal open arrangement. Air may readily enter the intake pipe 16 from outside of the building 12 and after passing through the tank 10, stack 15 and bowl 14 freely passes upwardly through the vent pipe 19 exhausting above the building 12. It will be seen that under normal conditions, the circulation of air through the bowl 14 provides a circulation therethrough of fresh air which has been passed through the disinfecting tank 10 and this renders the entire device sanitary by reason of its germ killing properties.

It will be understood that when the lid 24 is elevated, the rod 25 and lever 22 as well as the rod 21, will be elevated therewith as indicated by dotted lines in Fig. 1 of the drawing and which operation arranges the damper 20 in its closed position at the bottom of the intake pipe 16. At such times, the draft caused by the vent pipe 19 will draw air from the toilet room 26 within the building 12 and such air will pass through the bowl 14 and upwardly out of the vent

pipe 19, a complete circuit of ventilating air being thereby arranged at all times through the bowl 14.

In the structure herein shown, the shaft 23 is provided with a plurality of paddles 27 adapted for stirring up the disinfecting fluid 13 by rotating the shaft 23 upon the upward movement of the lever 22 it being noted that a pawl 28 carried by the lever 22 is adapted to engage a toothed wheel 29 secured to the said shaft for imparting a partial rotation to the latter during each opening movement of the lid 24. An automatically controlled ventilating system for a sanitary toilet is arranged adapted for operation in connection with a disinfecting device for rendering the structure entirely sanitary and germless.

While the form of the invention herein shown and described is believed to be the preferred embodiment thereof, minor changes may be made therein without departing from the spirit and scope of the invention as claimed.

25 What I claim as new is:—

1. A device of the class described comprising a disinfecting tank, an air intake pipe mounted upon the tank at one end thereof, an upright stack upon the opposite end of the tank, a bowl positioned upon the said stack, a hinged closure lid for the said bowl, a damper for the intake pipe within the tank, an outlet vent pipe for the bowl, and operative connections between the said lid and damper.

2. A device of the class described comprising a disinfecting tank, an air intake pipe mounted upon the tank at one end thereof, an upright stack upon the opposite end of the tank, a bowl positioned upon the said stack, a hinged closure lid for the said bowl, a damper for the intake pipe within the tank, an outlet vent pipe for the bowl, pivotal connecting rods between said damper and lid adapted for moving the damper to its open and closed positions during the closing and opening of the lid respectively.

3. A device of the class described comprising a disinfecting tank, an air intake pipe mounted upon the tank at one end thereof, an upright stack upon the opposite end of the tank, a bowl positioned upon the said stack, a hinged closure lid for the said bowl, a damper for the intake pipe within the tank, an outlet vent pipe for the bowl, pivotal connecting rods between said damper and lid adapted for moving the damper to its open and closed positions, and a swinging connector pivoted to the adjacent ends 60 of the said connecting rods.

4. A device of the class described comprising a disinfecting tank, an air intake pipe mounted upon the tank at one end thereof, an upright stack upon the opposite end of the tank, a bowl positioned upon the said

stack, a hinged closure lid for the said bowl, a damper for the intake pipe within the tank, an outlet vent pipe for the bowl, a pivoted lever within the tank, and rods connecting the said lever with the said damper and lid, whereby the opening of the lid is adapted for closing the damper and the closing of the lid is adapted for opening the damper.

5. A device of the class described comprising a toilet bowl adapted for positioning within a building, a disinfecting tank arranged beneath the building in communication with the bowl, an air intake pipe carried by the tank opening exteriorly of the building, a normally open hinged damper for the intake pipe and a normally closed hinged closure lid for the bowl, an outlet vent pipe for the bowl, and operative connections between the said lid and the damper whereby the damper is moved to a closed position upon opening the lid.

6. A device of the class described comprising a toilet bowl having an outlet vent pipe and a hinged closure lid, an air intake pipe, a damper for said intake pipe, the said damper being normally opened when the lid is closed with a free passage of air through the said intake pipe, bowl and vent pipe, and operative connections between the said damper and lid whereby the damper is closed when the lid is in its open arrangement and providing at such times a passage for air through the bowl and vent pipe.

7. A disinfecting means for a toilet, having a bowl provided with a vent pipe and a hinged closure lid, comprising a disinfecting tank communicating with the bowl beneath the same, a valved air inlet for the tank adapted for providing an air current into and through the tank, bowl and vent pipe whereby the air is disinfected prior to entering the bowl, and actuating means for the valve of the tank air inlet operatively connected to the lid of the bowl, substantially as described.

8. An automatically operated disinfecting means comprising in combination with a fluid-containing tank and a toilet bowl mounted thereon provided with a hinged lid, a shaft journaled in the tank, radially projecting perforated paddles carried by said shaft having paths of movement through the contents of the tank when the shaft is revolved, an operating lever journaled upon the shaft, a toothed wheel secured to the shaft adjacent the lever, a hooked pawl pivoted to the lever adapted for engaging said wheel and a curved rod connected between the said lever and lid whereby the shaft is adapted for partial rotation during each opening movement of the lid.

9. A disinfecting means for a toilet, having a bowl provided with a vent pipe and a hinged closure lid, comprising a disinfecting tank communicating with the bowl

- beneath the same, a valved air inlet for the tank adapted to provide an air current into and through the tank, bowl and vent pipe, whereby the air is disinfected prior to entering the bowl, an agitator within the tank, and actuating means for the agitator and the valve of the tank air inlet operatively connected to the lid of the bowl, substantially as described.
- 10 10. A disinfecting means for a toilet, having a bowl provided with a vent pipe and a hinged closure lid, comprising a disinfecting tank communicating with the bowl beneath the same, a valved air inlet for the tank adapted to provide an air current into and through the tank, bowl and vent pipe whereby the air is disinfected prior to entering the bowl, an agitator within the tank, an operating lever for said agitator, operating means for the lever adapted for automatic actuation during the opening of said

lid, and opening means for the valve of the tank air inlet automatically operable upon the closing of said lid.

11. A device of the class described comprising in combination with a disinfecting tank having an air inlet pipe and a stack, of a toilet bowl mounted upon the stack provided with a hinged closure lid and having an outlet vent pipe in communication with the inlet pipe through the tank and stack to provide an air current therethrough, a controlling damper for the air inlet pipe, a shaft journaled in the tank, agitating paddles upon the shaft, an operating lever on the shaft, connections between said lever and shaft, operative connections between the lever and said damper, and operative connections between said lever and said lid, substantially as described.

In testimony whereof I affix my signature.
EDWARD J. DE GUNTHER.
